UNITED STATES PATENT OFFICE.

NORBERT M. LA PORTE, OF BALTIMORE, MARYLAND, ASSIGNOR TO THE MOTOR COOLING SYSTEMS COMPANY, A CORPORATION OF MARYLAND.

CIRCULATOR-CHECK.

1,187,535.

Specification of Letters Patent. Patented June 20, 1916.

Application filed April 26, 1915. Serial No. 23,801.

To all whom it may concern:

Be it known that I, NORBERT M. LA PORTE, a citizen of the United States of America, and resident of the city of Baltimore, State 5 of Maryland, have invented certain new and useful Improvements in Circulator-Check, of which the following is a specification.

The principle involved in cooling the walls of the cylinder and combustion chamber of an internal combustion engine used to drive a road vehicle is well understood. Water is passed through the cylinder jacket and thence through a radiator, which is subject to a draft of air, and then back to the 10 water jacket. The circulation of the water in this way is accomplished by three different recognized methods. There is the system by which the hot water rises from the jacket to the top of the radiator and becomes cooled as it passes downward through the tubes of the radiator, while the water displaced from the radiator takes the place 15 of the heated water in the jacket which in turn is passed into the top of the radiator. 20 This circulation, which is termed thermostatic, is maintained by gravity which causes the denser water at the lower temperature to displace the water at a higher temperature which is of less specific gravity. 25 In either method, the circulation is maintained by means of a pump in the cooling system driven from the engine. In addition to these two, there is the system described in my co-pending application, Serial No. 80 30 876,184, in which the energy stored in the exhaust gases is imparted to the water increasing the rate of circulation. In this method, there is a gas nozzle in the circulating system, preferably turned in the direction of thermo-siphonic circulation, and connected by means of a tube to the manifold so that a portion of the exhaust gases pass 35 directly from the exhaust manifold to the nozzle and into the water, the circulation 40 of which is thus accelerated in proportion to the quantity of gas contained and therefore to the heating effect.

The circulation of the water and the consequent cooling of the engine while it is 45 running is the normal operation of the system and is desirable and even necessary to the successful operation of the engine, but when the engine is stopped, and particularly when it stands idle for a long period 50 and is subject to a comparatively low tem-

perature, circulation of the cooling water is not desirable, for a temperature of the engine parts approximating that which the engine attains in running under the most favorable conditions is desirable in starting, 60 and if the engine is permitted to cool, extensive priming and re-adjustment of the carburetor are necessary in order to start and run until the engine has reached the normal running temperature. It will be 65 apparent on consideration that in the ordinary cooling system, the thermo-siphonic circulation with consequent cooling of the water passing through the radiator and jacket, and hence of the engine, will continue 70 even though the engine is idle and cooling will terminate only when all parts reach the temperature of the atmosphere, so when the operator desires to start the engine, he finds it difficult and must resort to the expedients 75 which we have described, and even then the engine does not operate with normal efficiency until warmed up.

Radiator hoods and covers to prevent cooling are a familiar sight in all countries 80 where freezing temperatures are common, but even with the use of such protection, cooling of the engine to a temperature at which it will not start and operate efficiently 85 is the inevitable result if the car is left idle for a few hours in cold weather.

To provide means for retarding the cooling effect on an idle motor is the object of this invention. To this end I provide means which operate automatically when the engine stops to close the passage from the radiator to the water jacket and thus prevent circulation of the cooling water. Where the circulation is maintained by means of a pump or a circulator of the type previously 90 described herein, a check valve which opens in the direction of circulation and is held open by the circulation and is arranged to close when the circulation is arrested or falls below normal, may be used. With the 95 thermo-siphonic system in which circulation is merely dependent upon the heating effect and is much less active than with the forced circulation systems, means must be provided for opening the check valve when the engine starts and closing it when the engine stops. With the circulation of the cooling water thus checked or wholly stayed, cooling 100 of the engine while idle is practically eliminated and a running temperature may 105 110

be maintained for hours after the engine has stopped. Immediately on starting the engine, the valve opens either by pressure of the water or by operation of a device connected to the engine for that purpose, and the circulation of the water with the usual cooling effect begins. Thus, while the disadvantages incident to cooling of the engine when idle are avoided, the danger of over-heating by starting the engine, when the circulation is checked, is not incurred.

In the accompanying drawing I have illustrated an engine and portions of a cooling system to which my invention has been applied.

Figure 1 is a side elevation of an engine, radiator and connections provided with the circulator described in my co-pending application No. 876,184, and the circulator check of this invention; Fig. 2 is a detail of the check; Fig. 3 is a diagrammatic view showing the circulator check in connection with a pump; Fig. 4 shows the circulator check applied to a thermo-siphonic system, the check being actuated by means of the engine suction; Fig. 5 shows a somewhat similar arrangement with the check operated by the exhaust pressure; and Fig. 6 shows an electrical device for actuating the circulator check.

Referring to the drawing by numerals: the construction shown in Fig. 1 includes a radiator 1, a cylinder casting 2 with connections from the radiator to the water jacket at the top 3 and bottom 4. In the latter connection, I have shown my circulator consisting of a nozzle 5 in the bottom connection 4 and a tube 6 leading from the manifold to the nozzle. A portion of the exhaust gases passing through the tube is thus discharged and has the effect of accelerating the circulating action. I have also shown in this radiator connection a valve seat 7 with a check valve 8 adapted to open freely in the direction of circulation so that it does not interfere with the circulation, while the engine is running, but so arranged with any suitable means as a spring or the weight of the valve, or a weight in addition to the valve, that it will close when the engine stops and prevent circulation of the water while the engine is idle and consequent diffusion of the heat necessary to maintain the normal and most efficient temperature of the engine. The means for closing the valve may be a spring, gravity, pressure, vacuum or any suitable means and the intent of the claims is to include any and all such alternative and equivalent expedients.

In Fig. 3 I have shown diagrammatically a pump 9 together with the circulator check 10 consisting of a seat and a valve 8, which may be the same as that in the previous case, pivoted at 11 and so weighted or controlled by means of a spring 7 as to close

against thermo-siphonic circulation but adapted to be freely opened when subject to the circulating effect of the pump.

In the device shown in Fig. 4, the water is circulated by the thermo-siphonic system, through the radiator 1 and water jacket 12, inclosing the upper portions of the cylinder and combustion chambers in the cylinder casting 2. In the lower radiator connection 13, there is a valve 14 mounted to swing on a central transverse pivot 15 having an arm 16 at right angles to the pivot. This arm 16 which is rigidly secured to the valve shaft or pivot is connected at its end by means of a slot and pin 17 to a thrust rod 18 engaging a diaphragm 19, mounted centrally in a chamber 20. One side of this chamber is filled with air at atmospheric pressure and from the other side the air may be exhausted, as by way of a pipe 21 leading to the intake manifold 22.

Fig. 5 shows a similar device similarly operated by pressure led through a pipe 23 from the exhaust manifold 24.

In Fig. 6 I have shown electrically operated means for controlling the circulator check. In the form of the invention shown there is a gravity valve 25 which rests on the seat 26 through which the water in one of the connections in the circulating system passes in the direction of the arrows. The valve stem 27 is preferably of soft iron and acts as the core of the solenoid 28 which may be in circuit with the magneto, generator or ignition switch or any current, the flow of which is practically coincident with the operation of the motor. The valve tends to seat by the action of gravity or a spring 29 as shown, but when the circuit is closed just prior to, if it is a battery ignition or at the starting of the motor if it is the magneto or generator circuit, the solenoid 28 is energized and tends to draw the core 27 upward toward the center of the coil so that the valve 25 is lifted well off its seat and the circulating system is opened. So long as the engine runs, the solenoid retains its attraction for the core and the valve remains open. When the engine stops, the passage of current ceases and the valve being released returns to its seat by spring pressure or force of gravity, or both.

I have thus described various embodiments of my invention specifically and in detail in order that their nature and operation may be fully understood; however, the specific terms herein are used in their descriptive rather than in their limiting sense, and the scope of the invention is defined in the claims.

I claim—

1. In a water cooling system for internal combustion engines consisting of a water jacket, a radiator and connections between

the water jacket and radiator at the top of the engine to give thermostatic circulation, means for checking the circulation when the engine is idle consisting of a valve 5 in the connection and means for opening the valve when the engine starts and closing it when the engine stops.

2. In a water-cooling system for internal combustion engines consisting of a water jacket, a radiator and connections between the water jacket and radiator, means operating coincidentally with the engine for forcing the water through the system to give a continued cooling effect in the radiator, 10 a valve in the connections mounted to open in the direction of circulation and means having a slight tendency to close the valve so that it opens when the engine starts and closes when the engine stops.
- 20 3. In a water-cooling system for internal combustion engines consisting of a water

jacket, a radiator and connections at the top and bottom from the water jacket to the radiator arranged to give thermostatic circulation, means for forcing the water through the system continuously in the direction of thermostatic circulation, means operating coincidentally with the engine for checking the circulation to prevent cooling when the engine is idle, in the 25 form of a valve mounted to open in the direction of circulation when the engine starts and provided with means resisted by the circulation, tending to close the valve so that it closes when the engine stops. 35

Signed by me at Baltimore, Maryland, this 11th day of April, 1915.

ROBERT M. LA PORTE.
